UNITED STATES PATENT OFFICE.

NARY D. RAINVILLE, OF BRAIDWOOD, ILLINOIS.

SHOW-STAND.

SPECIFICATION forming part of Letters Patent No. 345,602, dated July 13, 1886.

Application filed November 6, 1885. Serial No. 182,055. (Model.)

To all whom it may concern:

Be it known that I, NARY D. RAINVILLE, a citizen of the United States, residing at Braidwood, in the county of Will and State of Illinois, have invented certain new and useful 5 Improvements in Show-Stands, of which the following is a specification.

My invention relates to improvements in those show-stands forming racks or supports 10 for cloaks or coats, in which the portion supporting the garments can be readily rotated, so as to bring any part to the point required, while at the same time the arms or brackets supporting each individual garment may be 15 readily separated from the remaining arms of the rack, so as to display any particular garment.

In order that the invention may be better understood, I will proceed to describe it with 20 reference to the accompanying drawings, in which—

Figure I is a vertical sectional view of my improved rack, and Fig. II is a plan view of the same. Fig. III is a perspective view 25 thereof.

The standard 1 is provided with legs or supports 2, and with an upwardly-projecting pin, 3, forming the axis of a loosely-revolving collar, 4. A button or head, 5, fixed upon the 30 upper end of pin 3 in any desired manner, while furnishing an ornamental finish to the pin, serves to prevent the collar's removal. A circular series of pivot pins or bolts, 6, is provided near the periphery of the collar 4,

and on such bolts are pivoted, so as to allow 35 free movement in a horizontal plane, a number of arms, 7.

Supported loosely in holes in the outer ends 40 of arms 7 are hooks 8, from which the garments are supported.

It will be seen that by rotating the collar 4 the whole body of garments supported on the rack may be swung around, so as to bring any particular one to the position desired; that then by separating the arms 7, as shown in 45 Fig. II, such single garment may be effectively displayed, while by turning it with its supporting-hook 8 any side of the garment may be brought to light.

The stand may be mounted on casters, so as 50 to permit it to be moved easily from one place to another.

Having thus described my invention, the following is what I claim as new therein and desire to secure by Letters Patent:

A show-stand consisting of a standard, 1, pin 3, collar 4, seated on the standard around the pin, a series of arms, 7, each having a support, 8, at its outer end, and a series of pivot-pins, 6, near the periphery of the collar, the 55 inner ends of the arms being hinged to the pins and resting on the collar, so as to be supported by the latter, substantially as described.

NARY D. RAINVILLE.
